UNITED STATES PATENT OFFICE.

SAMUEL NEILINGER, OF NEW YORK, N. Y.

DESIGN FOR A TRIMMING FOR LADIES' WEARING-APPAREL.

59,856.

Specification for Design.

Patented Nov. 29, 1921.

Application filed December 20, 1919. Serial No. 346,382. Term of patent 3½ years.

To all whom it may concern:

Be it known that I, SAMUEL NEILINGER, citizen of the United States, and resident of the borough of Manhattan, city of New York, in the county of New York and State of New York, have invented a certain new, original, and ornamental Design for a Trimming for Lady's Wearing-Apparel, of which the following is a specification, reference being had to the accompanying drawing, forming part thereof.

The drawing shows the design as applied to a piece of fabric for lady's wearing apparel.

I claim:

The ornamental design for a trimming for lady's wearing apparel as shown.

Signed at the borough of Manhattan, city of New York in the county of New York and State of New York, this 19th day of December, A. D. 1919.

SAMUEL NEILINGER.
